Gilbert Sherwood of Erie, State of Pennsylvania

Letters Patent.

The schedule referred to in this Letter Patent and making part of the same containing a description in the words of the said Gilbert Sherwood, himself of his improvement in the Crane

To all to whom these presents shall come,

Be it known that I, Gilbert Sherwood of Erie in the County of Erie and State of Pennsylvania, have invented a new and useful improvement in the Crane and that the following is a full and exact description thereof, — I, — a stationary Crane post designated by the letter A. A. in the accompanying draft (entitled "Sherwood Improved Crane"), casting perpendicularly on a step and secured in position by the fastens. B. B. This post is about fifteen feet high and fourteen inches in diameter at the bottom and ten inches at the top, on the top of the Crane Post is a pivot five inches in diameter and six long 2¹/₂ in. Crane cap marked D. D. in the said draft twelve inches wide and three inches deep and nine feet long with a hole twelve inches from the one end of the sufficient size to admit the pivot of the Crane Post. The cap is placed horizontally on the Crane post playing freely on the pivot. The opposite end being supported by the braces marked D. D. in said draft, — 3rd with saddle marked C. C. in said draft, this and a half feet long fourteen inches wide by twelve deep casting on the fastens and playing round the foot of the crane post at right angles to the crane cap, — 4th two braces marked D. D. in said draft, these braces are three inches thick by six deep and extend one from each end of the saddle to the end of the Crane Cap which they support. They are tenoned into the top of the saddle and bottom of the Crane Cap three inches from the end of each leaving at the

point of the Crane Cap three inches between the braces.

5. The windlass marked C, is the end draft three feet long and nine inches in diameter affixed to the side of the braces two feet from them, junction with the saddle by caps marked 5, in said draft, these caps are about six feet long and of the same thickness with the braces, to which they are fastened by bolts. The Partness D, is a base fifteen inches wide by twelve inches deep mounted horizontally by iron bolts, into iron bolts, to form vent splitting iron. Near the end of the Crane Cap, exactly between the ends of the braces is a hook for the purpose of fastening a tackle E, this hook is secured by an iron plate on the top of the Crane loop and is of sufficient strength to support several tons weight.

6. The stone hook marked in said draft with the letter H, this is made of a bar of iron one inch square, with a hook one foot long and shank three feet long with a becket attached to the handle, on the improved Crane's design to be used on board of boats in raising stones and any other heavy body from the water and in raising and lowering timber and stone in building of wharfs &c. in the features and principles by which it may be distinguished from other Cranes is the saddle and two braces, by means of which any amount of power may be applied to move the body suspended from the Crane, horizontally without danger of diminishing the strength of the crane or endangering its breaking, In use the Crane should be seated in the centre of the scow, and in addition to the partness the crane post is further supported by stay chains. In raising weight with the crane a tackle is fastened to the hook on the crane cap with the fall fastened to the windlass when the body is raised sufficiently, it is moved horizontally to the place desired on ^{is another tackle fixed to other part of the body} the scow, when the stone to be raised lies close to the ground the stone hook is forced under one end of it after which the

hook is hitched to the trace and the stone raised sufficient
to admit the wrapping chain beneath it
